(57) **CLAIM**

The ornamental design for the loudspeaker, as shown and described.

DESCRIPTION

The present design pertains to an acoustic transducer that may be used as a loudspeaker or may be used with other components in a loudspeaker system.

FIG. 1 is an upper-left front perspective view of a loudspeaker;

FIG. 2 is a front elevational view;

FIG. 3 is a right side elevational view with the left side elevational view being a mirror image thereof; and,

FIG. 4 is a top plan view with the bottom plan view being a mirror image thereof.

The undisclosed rear view forms no part of the claimed design.

The broken line showing on the drawing disclosure is for illustrative purposes only and forms no part of the claimed design.
